UNITED STATES PATENT OFFICE.

GEORGE D. NICHOLS, OF NEW CANAAN, CONNECTICUT.

GARMENT-SUPPORTER.

SPECIFICATION forming part of Letters Patent No. 532,244, dated January 8, 1895.

Application filed June 23, 1894. Serial No. 515,482. (No model.)

To all whom it may concern:

Be it known that I, GEORGE D. NICHOLS, a citizen of the United States, residing at New Canaan, in the county of Fairfield and State 5 of Connecticut, have invented certain new and useful Improvements in Garment-Supporters; and I do hereby declare the following to be a full, clear, and exact description of the invention, such as will enable others 10 skilled in the art to which it appertains to make and use the same.

My invention has for its object to simplify and cheapen the construction of garment supporters and also to greatly improve their operation in use, it being necessary in an article 15 of this class to reduce the cost of construction to the lowest possible limit and also to provide a construction which will hold the stocking, drawers or other garment that is to 20 be supported, securely, and so that there is no danger of its slipping, and also without danger 25 of tearing the garment.

With these ends in view I have devised the novel construction of which the following description in connection with the accompanying drawings is a specification, numbers and letters being used to designate the several parts.

Figure 1 is a front elevation of my novel supporter the sliding stud being in the engaged position; Fig. 2, a side elevation corresponding therewith; Fig. 3, a front elevation, the sliding stud being in the retracted position, that is, in position for attachment to a stocking or other garment, and Fig. 4 is a side elevation corresponding therewith.

My novel supporter consists of a body portion formed of wire which I designate as A, a swinging loop hinged thereto also made of 40 wire which I designate as B and a sliding stud which is designated as C. The central portion of the body consists of parallel sides designated by 2 upon which the loop 3 of the sliding stud is adapted to move. The upper 45 end of the body is made widest and is provided with a cross piece 4 so as to form openings 5 through which the web is passed, the web being attached in the usual manner, that is to say it is passed through from the back, 50 over the cross piece, then under the parallel sides, then through opening 6 at the bottom of the body where it is attached. The swinging loop is hinged to the body as at 7 and is curved outward forming an opening 8 through

which the stud with a fold of garment thereon 55 will pass freely. Below opening 8 is a neck 9 over which the stud passes when it is moved to the engaged position.

An important feature of my novel construction is that the lower portion of the body is 60 inclined backward as at 10 and the lower portion of the swinging loop is inclined forward as at 11 so that when the sliding stud is moved to the engaged position the innersides 65 of the swinging loop where it narrows inward to form the neck will bear upon the parallel sides as at 12, thus creating a spring action which causes the neck to lie close under the sliding stud when in the engaging position, and hold the fold of stocking or 70 other garment securely in place.

The operation is the same as in other devices of this class. The sliding stud being in the position shown in Figs. 3 and 4, the operator places a fold of the stocking or other 75 garment that is to be held over the stud, then presses the swinging loop down upon it and draws the web, and with it the body and swinging loop upward so that the neck of the loop will pass under the stud and will force 80 the fold of garment close up under the head of the stud thus retaining the garment firmly with a spring pressure but in such a manner as to do away with all danger of tearing the 85 garment.

Having thus described my invention, I claim—

A garment supporter consisting of a body having openings for the attachment of a web and having parallel sides, a swinging loop 90 having an opening adapted to receive a stud, said body and swinging loop being pivoted together and inclined away from each other at their lower portion, a neck or ledge formed on said loop by the contracted lower portion 95 and adapted to come into contact with the parallel sides of the body portion, a stud mounted to slide upon said ledge and positively held in its operative position by the spring action of the body and loop resulting 100 from the opposing inclinations, substantially as described.

In testimony whereof I affix my signature in presence of two witnesses.

GEORGE D. NICHOLS.
